ISIDORE MUND AND MEYER STARR, OF DETROIT, MICHIGAN.

CHECK-PROTECTOR.

1,364,575.

Specification of Letters Patent.

Patented Jan. 4, 1921.

Application filed September 9, 1920. Serial No. 409,131.

To all whom it may concern:

Be it known that we, ISIDORE MUND and MEYER STARR, citizens of the United States, and residing at Detroit, county of Wayne 5 and State of Michigan, have invented a new and improved Check-Protector, of which the following is a specification.

This invention relates to means for perforating, imprinting or embossing checks 10 and other commercial papers with numerals, letters or other characters in such a manner that the sum or amount indicated thereby cannot be varied, and its object is to provide a simple and effective protecting mechanism 15 of such small size that it may be carried in a coat pocket, and which shall be so simple in construction that it can be produced at low cost.

This invention consists of a case and a 20 guide therein, a series of chains slidable around the guide, each link being provided with a raised character, means to move the chains independently of each other, and a platen hinged to the case and provided with 25 a row of dies adapted to coöperate with the characters on the links to emboss, perforate or otherwise multilate the commercial papers which are placed upon the platen.

It further consists in the details of construction illustrated in the accompanying drawings and particularly pointed out in the claims.

In the drawings, Figure 1 is a side and Fig. 2 an end elevation of this novel perforating device. Fig. 3 is a section on the line 3—3 of Fig. 5. Fig. 3^a is a detail of the chain guide on a larger scale. Fig. 4 is a section on the line 4—4 of Fig. 3. Fig. 5 is a plan of the device. Fig. 6 is a plan of a 40 part of the platen with the dies removed. Fig. 7 is a perspective of one of the links. Fig. 8 is a plan of a perforating die on a large scale. Fig. 9 is a view similar to Fig. 1 with the case swung up.

Similar reference characters refer to like parts throughout the several views.

The case shown in the drawings comprises a top 1 and the sides 2 between which extends the tubular guide 3 for the chains 4. The metal of this guide may be struck up at intervals to constitute the lips 5 between which these chains are slidable, as shown in Fig. 4. Each chain is preferably built up of ten links 6, one for each digit, 55 but any additional number of links can be provided for if additional characters are to

be used. Each link is preferably provided with a transverse notch 7 to receive the alining rib 8 on the guide; although this alining device may be omitted, as shown in Fig. 7, 60 we prefer to form the link with perforated ends 9 adapted to extend between the ears 10 of the next adjacent link and be attached thereto by means of pins 11.

A shaft 13 extends across within the case 65 and supports the star-wheels 14 whose teeth extend out through the opening 15 in the case and also extend into the inclined-sided notches 16 in the links. These teeth enable the wheels to be turned and the chains to be 70 slid around on the guide 3 to bring any desired links in alinement with the dies on the platen. The rib 8 is formed on the guide to properly aline these selected links as indicated in Fig. 3^a. 75

At the end of the case opposite the shaft 13 is a hinge 18 on which is mounted the platen 19 in the form of a flat plate across which extend the bars 20 and 21. A spring 23 tends to swing down the platen, but this 80 is normally prevented by the latch 24. A resilient rectangular frame 25 is attached to the cross bar 20 for the purpose of stripping the perforated paper from the characters on the links, when the machine is 85 constructed for perforating.

Any desired devices may be employed to impress the desired characters on the paper. Those shown consist of numerals formed of short sections 26 (Fig. 7), each constituting 90 a punch adapted to enter one of the holes 27 in the die 28, the various numerals being so formed that portions thereof will register with these holes 27 in such a manner that any desired figures can be indicated by 95 perforations. One of these dies is secured to the holder 21 therefor for each chain 6 and is so positioned that it will register with the characters on the links when the links are alined by the rib 8 on the chain guide. 100 Short partitions 30 on the die holder 21 hold these dies in proper position. It will be understood that any other impressing or embossing mechanism in common use may be substituted for these perforating devices 105 which are preferred as no inking mechanism is required.

In Fig. 6 we have indicated the words Pay and Only as examples of letters or characters which may be impressed on the commercial papers at the ends of the amounts, 110 but these as well as all the details of con-

struction may be varied by those skilled in the art without departing from the spirit of our invention as set forth in the following claims.

5. We claim:—

1. In a protecting device, the combination of a case and a guide therein having a longitudinal rib, a series of chains slideable around the guide and having characters on the outer 10 faces of the links and notches on the inner faces of the links adapted to receive the rib on the guide to aline the links, and a platen hinged to said case and adapted to press pieces of paper against the characters on the 15 links.

2. In a protecting device, the combination of a case and a guide therein having a longitudinal rib, a series of chains slideable around the guide and having characters on the outer 20 faces of the links and notches on the inner faces of the links adapted to receive the rib on the guide to aline the links, a platen hinged to said case and adapted to press pieces of paper against the characters on the 25 links, and means mounted on the platen to pull the imprinted paper from the links.

3. In a protecting device, the combination of a case and a guide therein having a longitudinal rib, a series of chains slideable around 30 the guide and having characters on the outer faces of the links and notches on the inner faces of the links adapted to receive the rib on the guide to aline the links, a platen hinged to said case and adapted to press pieces of paper against the characters on the 35 links, a series of dies mounted on the platen and adapted to co-act with the characters on the links to perforate pieces of paper, and means to pull such pieces of paper from the 40 links.

4. In a protecting device for commercial papers, the combination of a case, a tubular guide within the case, a series of chains slideable around the guide and having elevated 45 characters on the outer faces of the links, a shaft extending across the case parallel to the guide, a toothed wheel mounted on said

shaft for each chain and in engagement therewith whereby the chain may be slid around the guide, and a platen hinged to the 50 case and adapted to press the pieces of paper against the characters on the links, said links having notches in their inner faces and the guide having a longitudinal rib adapted to enter said notches to aline the links. 55

5. In a protecting device for commercial papers, the combination of a case, a tubular guide within the case, a series of chains slideable around the guide and having elevated characters on the outer faces of the links, a 60 shaft extending across the case parallel to the guide, a toothed wheel mounted on said shaft for each chain and in engagement therewith whereby the chain may be slid around the guide, a platen hinged to the case 65 and adapted to press the pieces of paper against the characters on the links, and means mounted on the platen to pull the imprinted paper from the links.

6. In a protecting device for commercial 70 papers, the combination of a case, a tubular guide within the case, a series of chains slideable around the guide and having elevated characters on the outer faces of the links, a 75 shaft extending across the case parallel to the guide, a toothed wheel mounted on said shaft for each chain and in engagement therewith whereby the chain may be slid around the guide, a platen hinged to the case and adapted to press the pieces of paper 80 against the characters on the links, a series of dies mounted on the platen and adapted to co-act with the characters on the links to perforate pieces of paper, and means to pull such pieces of paper from the links. 85

7. The combination of a guide and means to support the guide, a series of chains slideable around the guide and having characters on the outer faces of the links, a platen hinged to the guide support to press paper 90 against the links, and means to pull the imprinted paper from the links.

ISIDORE MUND.
MEYER STARR.
